UNITED STATES PATENT OFFICE.

ALFRED T. MANNING, OF KANSAS CITY, MISSOURI.

DESIGN FOR A RADIATOR CAP.

Application filed August 11, 1926. Serial No. 18,689. Term of patent 14 years.

To all whom it may concern:

Be it known that I, ALFRED T. MANNING, a citizen of the United States, residing at Kansas City, in the county of Jackson and State of Missouri, have invented a new, original, and ornamental Design for a Radiator Cap, of which the following is a specification, reference being had to the accompanying drawing, forming part thereof,

Fig. 1 is a front elevation of my new design for a radiator cap.

Fig. 2 is a side elevation of the same.

I claim:

The ornamental design for a radiator cap, as shown.

ALFRED T. MANNING.
